UNITED STATES PATENT OFFICE.

THOMAS LA MAIDA, OF NEW YORK, N. Y.

BUCKLE.

1,368,037.

Specification of Letters Patent.

Patented Feb. 8, 1921.

Application filed October 18, 1919. Serial No. 331,904.

To all whom it may concern:

Be it known that I, THOMAS LA MAIDA, a citizen of the United States, and a resident of New York, borough of Bronx, in the 5 county of Bronx and State of New York, have invented certain new and useful Improvements in Buckles, of which the following is a full, clear, and exact specification.

This invention relates more particularly 10 to a class of devices for use in conjunction with belts adapted to be worn by persons.

My invention has for its object primarily to provide a buckle designed to be employed for detachably fastening together the ends 15 of belts especially of a class made for personal wear, and which is of a form including one or a number of coacting elements adapted to be removably applied to a belt in a manner whereby the necessity of first ar- 20 ranging the device on the belt and afterward providing the customary loop or loops for holding the buckle may be avoided, besides serving when the buckle is employed on belts of washable material to allow the 25 buckle to be easily removed prior to cleaning the belt as well as serving to permit interchangeable belts to be used with the device. The invention consists essentially of a bar extending crosswise of a frame ele- 30 ment, and one part of the bar is held to the frame element, while its other part is free of the element so that it may be moved toward and from the element to allow of being removably disposed in the loop of a belt for 35 mounting the frame element on the belt, and on the bar is a locking element for releasably fastening the frame element and the free end of the bar together.

A further object of the invention is to 40 provide a buckle of a simple, efficient and durable construction which may be made of any suitable material in various shapes and sizes.

With these and other objects in view the 45 invention will be hereinafter more fully described with reference to the accompanying drawing which forms a part of this specification in which similar characters of reference indicate corresponding parts in all the 50 views, and will then be pointed out in the claims at the end of the description.

In the drawing, Figure 1 is a fragmentary view, showing a plan of one form of my improved buckle as used with a belt for detach- 55 ably fastening the ends of the belt together.

Fig. 2 is a fragmentary sectional view taken on the line 2—2 of Fig. 1.

Fig. 3 is an enlarged fragmentary sectional view taken on the line 3—3 of Fig. 1.

Fig. 4 is a perspective view of the clasp 60 element used in the buckle.

Fig. 5 is a fragmentary view showing a plan of a different form of buckle employed for fastening the ends of a belt together.

Fig. 6 is a fragmentary sectional view 65 taken on the line 6—6 of Fig. 5, and

Fig. 7 is an enlarged perspective view of a clip or sleeve used in conjunction with the buckle.

The form of the buckle illustrated in Figs. 70 1, 2, 3, 4, 7, consists of a slide element 10, a clasp element 11 and a complemental ring element 12 adapted to be detachably engaged by the clasp element, all of which may be made of metal or other suitable material 75 of any desired size and shape.

The slide element 10 has a substantially rectangular frame 13 to provide side members 14, 15 and end members 16, 17. To the central part of the member 16 is integrally 80 formed or otherwise held one end of a bar 18 extending crosswise of the opening of the frame so that its other end is in spaced proximity to the end member 17 of the bar, and this bar is preferably of a length as 85 well as being sufficiently yielding or pliable so that its free end may be sprung or moved from and toward the frame. Protruding from a corresponding part of the end member 17 of the frame is a lug or short bar 19 90 which is disposed on alinement with the spring bar 18 so that its free end is in closely spaced proximity to the free end of the bar 18. The bar 18 may be somewhat wider than the lug 19, and the free end part of the 95 bar may be reduced, as at 20, to a size similar to the size of the lug. Shoulders 21 and 22 are thereby provided at the juncture of the reduced part 20 with the remainder of the bar 18. In order to allow the bar 18 of 100 the frame of the slide to be releasably fastened to the lug 19 a locking element or sleeve 23 is provided. This sleeve is arranged on the reduced part 20 of the bar 18, and the sleeve is of a size so that it is freely 105 slidable on the bar for being partially moved upon the free end of the lug 19. The sleeve is also of a length similar to the length of the reduced part of the bar 18 to permit the bar and sleeve to clear the lug 19 when 110

sprung in spaced relation to the lug, and the shoulders 21 and 22 serve as stops to limit the movement of the sleeve on the bar. At the end of the sleeve 23 which is adjacent to 5 the lug 19 may be provided a teat or knob, as 24, while in the lug may be provided a socket, not shown, for receiving the knob 24 to releasably hold the sleeve against accidental movement when engaging the lug 19. 10 Also projecting from the edge of the bar 18 which is opposed to the side member 15 of the frame are two spaced teeth 26 and 27 which are adapted to engage the belt, as will be hereinafter explained, for preventing 15 the slide from slipping transversely of the belt as well as serving to prevent tendency of the belt to pucker or lay unevenly.

The clasp element 11 has a substantially rectangular frame 28 to provide side members 29, 30 and end members 31, 32. The side member 29 consists of a bar 33 of spring or pliable metal which extends from the end member 31, and this bar terminates with a free end in spaced relation to the end member 32 of the frame 28 for being adapted to be yieldingly moved toward and from the end member 32. Protruding from the end member 32 toward and on alignment with the bar 33 is a lug 34 having its free end in 30 closely spaced proximity to the free end of the bar. The free end part of the bar 33 is also reduced, at 35, and on this reduced portion is a locking element or sleeve 36 of a size for being slidably guided so that a portion 35 of the sleeve will be removably disposed on the lug 34 to detachably fasten the bar 33 and the lug 34 together. At one end of the sleeve 36 may be a teat or knob 37, and in the lug 34 may be a socket 38, Fig. 3, which 40 is arranged for receiving the knob of the sleeve when moved upon the lug so that the sleeve will be held to the lug against accidental movement, and protruding from the spring bar 33 toward the side member 30 of the frame are two spaced teeth 39 and 40. As shown the bar 33 lug 34 and sleeve 36 are preferably of similar formations to the bar 18, lug 19 and sleeve 23 of the slide element 10. Projecting from the outer edge of 50 the side member 30 of the frame 28 is a hook member 41 adapted to removably engage the complementary ring element 12 when arranged accordingly.

The ring element 12 has a substantially 55 rectangular frame 42 to provide side members 43, 44 and end members 45, 46. Extending into the opening of the frame 42 from its side member 44 may be a number of spaced teeth 47, 48, 49, and from the outer edge of 60 the side member 43 of the frame may be a plate or tongue, as 50, which projects on a similar plane to the frame. When this type of the buckle is removably applied to a belt, as 51, in one end of the belt is provided a loop 65 52. The sleeve 23 of the slide element 10

is moved entirely upon the reduced end 20 of the bar 18 of the slide element, and after springing the sleeve with the free end of the bar from the frame 13 of the slide element the bar 18 with the sleeve 23 are passed through 70 the loop 52 of the belt. By then moving the sleeve 23 so as to engage the lug 19 of the frame 13 the slide element will be removably held to the belt. Before the slide element 10 is applied to the belt the looped end 52 of 75 the belt is passed through the frame 42 of the ringlike element 12, and by arranging the looped end of the belt so that it laps upon the body of the belt a second loop, as 53, is provided in the same end of the belt. The 80 body of the belt is then guided under the side member 14 of the frame 43 of the slide element, over the loop 52 of the belt and under the side member 15 of the frame of the slide element. By moving the slide element 85 10 on the belt the loop 53 of the belt will be lengthened or reduced for likewise lengthening or shortening the belt, as is common to the manner of adjusting belts of such types. At the second end of the belt is provided 90 another loop, as 54, and the clasp element 11 is applied to this looped end of the belt by slidably moving the sleeve 36 upon the reduced end 35 of the bar 33 so that the sleeve is clear of the lug 34. The free end part bar 95 33 is then sprung from the frame 32 of the clasp element, and the bar with the sleeve are removably disposed through the loop 54 of the belt, after which the sleeve 32 is adjustably moved upon the lug 34. By then directing the hook 41 into engagement with the side member 43 of the frame of the ringlike element 12 the parts of the buckle will be clasped together for also fastening the end parts of the belt. As indicated, the 105 teeth 26 and 27 of the slide element 10, the teeth 39 and 40 of the clasp element 11, and the teeth 47, 48, 49 of the ringlike element 12 are provided so that they engage the material of the belt, and in turn these elements 110 will be prevented from moving out of their normal positions and the belt will also be prevented from puckering.

In Figs. 5 and 6 are illustrated a form of the buckle having only one element, and this buckle is composed of a frame 55 which is preferably substantially rectangular to provide side members 56, 57 and end members 58, 59. Projecting from the central part of the end member 58 is a bar 60 of a length so that its second end terminates in spaced relation to the end member 59 of the frame 55. The bar 60 is of yielding material so that its free end part may be sprung outward and toward the frame, and the free end portion of the bar may be somewhat reduced in size, as at 61. On this reduced part of the bar is a slidably sleeve 62 which is of a length approximately similar to the length of the reduced part, and extending from the end 130

member 59 of the frame 55 is a lug 63 disposed on alinement with the bar 60 as well as being in closely spaced proximity to the bar so that the sleeve 62 when moved accordingly on the bar 60 will also engage the lug 63. In the sleeve 62 at the end of the bar 60 may be a teat or knob 64, while in the lug 63 may be a socket 65 for receiving the knob 64 when the sleeve 62 is moved upon the lug 63, in order to releasably fasten the bar and the lug together. The bar 60, sleeve 62 and lug 63 are similar to the formations of like parts of the slide element 10 and clasp element 11 of the hereinafter described form of the buckle shown in Figs. 1, 2, 3, 4, 7 and protruding from the side member 57 of the frame 55 toward the bar 60 may be a number of teeth 66. This form of the buckle is applied to a belt, as 67, by providing at one end of the belt a loop 68. The sleeve 62 of the bar 60 is moved upon the reduced end 61 of the bar so that it is clear of the lug 63, and when the bar is sprung from the frame 55 it is passed through the loop 68 of the belt. Following readjustment of the sleeve 62 on the bar 60 and on the lug 63 the buckle will be removably held on the belt. When it is desired to detachably fasten both ends of the belt together the second end part of the belt is guided under the side member 57 of the frame 55, then the belt is passed over the bar 60 and under the side member 56 of the frame. The ends of the belt will thereby be detachably connected. Thus I provide a buckle of a type adapted to be applied to a belt in a manner whereby the buckle may be readily removed to allow of the use of interchangeable belts as well as permitting belts of washable material to be separated from the buckle when it is desired to clean the belt.

In the foregoing description, I have embodied the preferred form of my invention, but I do not wish to be understood as limiting myself thereto, as I am aware that modifications may be made therein without departing from the principle or sacrificing any

of the advantages of this invention, therefore I reserve to myself the right to make such changes as fairly fall within the scope thereof.

Having thus described my invention, I claim as new and desire to secure by Letters Patent:—

1. In a buckle, a toothed bar extending crosswise of a frame element, a lug protruding from an opposite part of the frame element so that the free end of the lug is closely spaced from the free end of the toothed bar, and a sleeve on the free end of the toothed bar, adapted to be slidably moved upon the lug for bridging the space between the toothed bar and said lug.

2. In a buckle, a yielding toothed bar extending crosswise of a frame element, a lug protruding from an opposite part of the frame element so that the free end of the lug is closely spaced from the free end of the toothed bar, a sleeve on the free end of the toothed bar, adapted to be moved upon the lug for bridging the space between the bar and lug, and a knob on the sleeve, said lug having a socket for removably receiving the knob when the sleeve is adjustably moved upon the lug.

3. The combination, in a buckle, of a frame element, a toothed bar extending crosswise of the frame element, a lug protruding from an opposite part of the frame element so that the free end of the lug is closely spaced from the free end of the toothed bar, a sleeve on the free end of the toothed bar, adapted to be slidably moved upon the lug for bridging the space between the toothed bar and said lug, and means for detachably fastening the sleeve and lug together when the sleeve is moved upon the lug.

This specification signed and witnessed this 15th day of October A. D. 1919.

THOMAS LA MAIDA.
